CRYSTAL HOLDER

Kurt Lowitzsch, Yonkers, N. Y., assignor, by mesne assignments, to North American Philips Company, Inc., New York, N. Y., a corporation of Delaware

Application October 25, 1952, Serial No. 316,897

9 Claims. (Cl. 250—51)

This invention relates to a crystal holder, and more particularly to an improved holder for a flat single crystal plate for use in crystal analysis X-ray units.

Heretofore, crystal holders of the type previously known had to be changed each and every time a crystal plate of different size and shape was substituted for the crystal plate then in use. The substitution of crystal holders thus necessitated the recalibration of the X-ray unit since the alignment or calibration of the X-ray unit was disturbed by the change in crystal holders.

An improved crystal holder embodying the present invention eliminates the aforesaid difficulties of previously known crystal holders by providing a universal crystal holder which may be used to accommodate crystal plates of various sizes and shapes as well as wafers with a burred edge which may be interchanged without disturbing the alignment or calibration of the X-ray unit.

It is an object of the present invention to eliminate the necessity of using several crystal holders of various sizes, by providing a crystal holder embodying the present invention which will accommodate a variety of types and shapes of crystals.

A further object of the present invention is to provide a crystal holder with a vertical banking surface which is so constructed as to permit the use of wafers having a burred edge thereon.

Another object is the provision of a crystal holder with a horizontal banking surface which may be adjusted in a vertical direction in order to accommodate various sizes of crystal plates. In addition, the horizontal banking surface may be locked in a desired position thereof.

The above and other features, objects and advantages of the present invention will be fully understood from the following description considered in connection with the accompanying drawings.

Fig. 1 is a perspective view of the crystal holder embodying the present invention.

Fig. 2 is a side elevational view thereof, partly in section with the split-collar attachment removed.

Referring now more particularly to the drawings, the crystal holder embodying the present invention comprises a supporting member referred to generally by the numeral 10. Said supporting member has a cylindrical lower part 12 with a central, hollowed-out portion 14 as clearly seen in Fig. 2. A cylindrical plunger 16 is mounted for vertical movement in hollowed-out portion 14 with a light push fit, so that upon movement of said plunger vertically the outer periphery thereof frictionally engages the inner periphery of the hollowed-out portion 14 of said cylindrical lower part 12 and prevents slippage in any position thereof.

Supporting member 10 has an L-shaped upper part 18 which is preferably integral with said cylindrical lower part 12. Upper part 18 is provided with a vertical banking and reference surface 20 having a slit-like opening or recess 22 for the X-ray beam of the pre-set, associated X-ray unit.

2

Plunger 16 is provided with an anvil 17 at one end thereof, the anvil being perpendicular to the plunger 16 and having a top forming a horizontal banking surface 19. A V- or U-shaped groove 21 is cut into the horizontal banking surface 19. It will be noted that a portion of the outer periphery of plunger 16 rides in an arcuate groove 23 formed in upper part 18 of supporting member 10.

The vertical banking and reference surface 20 is adapted to accommodate a variety of shapes and sizes of crystal plates and wafers. Crystal 24 as seen in Fig. 1 is round or disc-shaped, while crystal 26 of Fig. 2 is a rectangular wafer having a burred edge 28. All crystals or wafers to be analyzed must be held with one face thereof engaging the vertical banking and reference surface 20 and in most cases an edge portion thereof engaging the horizontal banking surface 19. As seen in Fig. 1, crystal 24 is centered on the horizontal banking surface 19 by means of V-shaped groove 21. Rectangular crystals, on the other hand, may have a side edge portion abutting horizontal banking surface 19. It is preferred that the banking surfaces be made of a material having a very high resistance to wear, for example, carboloy.

It will be observed that upper part 18 of supporting member 10 has a recessed surface 30 which is undercut in order to accommodate a wafer which may have a burred edge, as shown in Fig. 2.

In order to fix a crystal or wafer in its proper, predetermined position, a pressure shoe lever 32 is pivoted to upper part 18 at 33. Pivoted at 34 to lever 32 is pressure shoe 36 which is preferably made of a transparent composition, thus facilitating the observation of the crystallographic axis direction marked on a crystal plate. A spring 38 engages the lever 32 and urges the pressure shoe 36 against a crystal or wafer with sufficient pressure to hold said crystal or wafer in its desired position, while another spring 40 functions to maintain one edge of the pressure shoe 36 substantially parallel to the vertical banking surface and permits the shoe 36 to align itself upon engagement with said crystal or wafer. A set screw 42 journaled in upper part 18 operates to engage and lock plunger 16 through cushion pin 43 in any desired position thereof in order to insure the maintenance of the desired setting of the horizontal banking surface.

The horizontal banking surface is preferably adjustable over a range of distances from $\frac{1}{4}$ inch to $\frac{3}{4}$ inch below the horizontal central line of the X-ray beam opening. It must be noted that a plane through the vertical banking and reference surface of the present crystal holder coincides with the longitudinal axis of cylindrical lower part 12.

Positioned on the lower part 12 is a movable split-collar attachment 44 which may be adjusted vertically and fixed at a desired height in order to maintain the crystal holder in its proper alignment position with respect to the X-ray beam. An adjustable screw 46 is mounted in the split-collar attachment 44 for causing the latter to be clamped at the desired height, thus preventing rotation of the split-collar attachment around lower part 12. Adjacent to pivot 33 is an adjustable screw 48 which, when turned, will cause supporting member 10 to move vertically in relation to split-collar attachment 44 and operates as a micro, vertical adjustment for the present crystal holder.

It will be apparent that the present universal crystal holder described more particularly hereinbefore may be adjusted to accommodate different crystal sizes and shapes or change from measuring crystal plates to wafers without disturbing the alignment or calibration of its associated crystal analysis X-ray unit.

While I have shown and described the preferred embodiment of my invention, it will be understood that the latter may be embodied otherwise than as herein specifically illustrated or described and that in the illustrated embodiment certain changes in the details of construction and in the arrangement of parts may be made without departing from the underlying idea or principle of the invention within the scope of the appended claims.

What is claimed is:

1. A crystal holder for use in crystal analysis X-ray units comprising a hollow shaft supporting member being provided at one end with a vertical banking surface, a vertically movable plunger in said hollow shaft supporting member, a part at the end of said plunger closest to said vertical banking surface being positioned substantially perpendicular to said plunger and having a portion thereof forming a horizontal banking surface, said horizontal banking surface being adjustable to accommodate a variety of crystals, a lever pivoting on said supporting member, and a member secured to said lever and adapted to frictionally hold a portion of said crystal in engagement with said vertical banking surface.

2. A crystal holder for use in crystal analysis X-ray units comprising a hollow shaft supporting member being provided at one end with a vertical banking surface, a plunger movable vertically and co-axially of said supporting member, an integral part at the end of said plunger closest to said vertical banking surface being positioned substantially perpendicular to said plunger and having a portion thereof forming a horizontal banking surface, said horizontal banking surface being adjustable to accommodate a variety of crystals, a lever pivoting on said supporting member, and a pressure shoe secured to said lever and adapted to frictionally hold a portion of said crystal in engagement with said vertical banking surface while an edge portion of said crystal abuts said horizontal banking surface.

3. A crystal holder for use in crystal analysis X-ray units comprising a hollow shaft supporting member being provided at one end with a vertical banking surface, said supporting member being recessed relative to said vertical banking surface at a portion adjacent to said vertical banking surface, a vertically movable plunger in said hollow shaft supporting member, an integral part at the end of said plunger closest to said vertical banking surface being positioned substantially perpendicular to said plunger and having a portion thereof forming a horizontal banking surface, said horizontal banking surface being adjustable to accommodate a variety of crystals, a spring-loaded lever pivoting on said supporting member, and a member secured to said lever and adapted to frictionally hold a portion of said crystal in engagement with said vertical banking surface while another portion of said crystal abuts said horizontal banking surface.

4. A crystal holder for use in crystal analysis X-ray units comprising a hollow shaft supporting member being provided at one end with a vertical banking surface, said supporting member being recessed relative to said vertical banking surface at a portion adjacent to said vertical banking surface, a vertically movable plunger in said hollow shaft supporting member, an integral part at the end of said plunger closest to said vertical banking surface being positioned substantially perpendicular to said plunger and having a portion thereof forming a horizontal banking surface, said horizontal banking surface being adjustable and grooved to accommodate a variety of crystals, a lever pivoting on said supporting member, and a pressure shoe member pivotally secured to said lever and adapted to frictionally hold a portion of said crystal in engagement with said vertical banking surface while another portion of said crystal abuts said horizontal banking surface.

5. A crystal holder for use in crystal analysis X-ray units comprising a hollow shaft supporting member being

provided at one end with a vertical banking surface, a vertically movable plunger in said hollow shaft supporting member, a part at the end of said plunger closest to said vertical banking surface being positioned substantially perpendicular to said plunger and having a portion thereof forming a horizontal banking surface, said horizontal banking surface being adjustable to accommodate a variety of crystals, a lever pivoting on said supporting member, a member secured to said lever and adapted to frictionally hold a portion of said crystal in engagement with said vertical banking surface while another portion of said crystal abuts said horizontal banking surface, and locking means in said supporting member for locking said plunger.

6. A crystal holder for use in crystal analysis X-ray units comprising a hollow shaft supporting member being provided at one end with a vertical banking surface, said supporting member being recessed relative to said vertical banking surface at a portion of said supporting member adjacent to said vertical banking surface, a plunger mounted for limited vertical movement in said hollow supporting member, an anvil at one end of said plunger having a top face forming a horizontal banking surface, said horizontal banking surface being adjustable to accommodate a variety of crystals, a side of said anvil abutting said recess, a lever pivoting on said supporting member, and a member secured to said lever and adapted to frictionally hold a portion of said crystal in engagement with said vertical banking surface while another portion of said crystal abuts said horizontal banking surface.

7. A crystal holder for use in crystal analysis X-ray units comprising a hollow shaft supporting member being provided at one end with a vertical banking surface, a vertically movable plunger in said hollow shaft supporting member, a part at the end of said plunger closest to said vertical banking surface being positioned substantially perpendicular to said plunger and having a portion thereof forming a horizontal banking surface, said horizontal banking surface being adjustable to accommodate a variety of crystals, a lever pivoting on said supporting member, and a member secured to said lever and adapted to frictionally hold a portion of said crystal in engagement with said vertical banking surface while another portion of said crystal abuts said horizontal banking surface.

8. A crystal holder for use in crystal analysis X-ray units comprising a hollow shaft supporting member being provided at one end with a vertical banking surface, a vertically movable plunger in said hollow shaft supporting member, a part at the end of said plunger closest to said vertical banking surface being positioned substantially perpendicular to said plunger and having a portion thereof forming a horizontal banking surface, said horizontal banking surface being adjustable to accommodate a variety of crystals, a lever pivoting on said supporting member, a split-collar member slideable on said supporting member and means for frictionally clamping said split-collar member on said supporting member.

9. A crystal holder for use in crystal analysis X-ray units comprising a hollow shaft supporting member being provided at one end with a vertical banking surface, a vertically movable plunger in said hollow shaft supporting member, a part at the end of said plunger closest to said vertical banking surface being positioned substantially perpendicular to said plunger and having a portion thereof forming a horizontal banking surface, said horizontal banking surface being adjustable to accommodate a variety of crystals, a lever pivoting on said supporting member, a split-collar member slideable on said supporting member, means for frictionally clamping said split-collar member on said supporting member, and means for connecting said supporting member to said split collar member to thereby adjust said supporting member vertically relative to said split-collar member.

10. A crystal holder for use in crystal analysis X-ray units comprising a hollow shaft supporting member being provided at one end with a first banking surface coinciding substantially with the longitudinal axis of said supporting member, a plunger movable in said hollow shaft supporting member, a part at the end of said plunger closest to said vertical banking surface being positioned substantially perpendicular to said plunger and having a portion thereof forming a second banking surface, said second banking surface being adjustable to accommodate a variety of crystals, and means mounted on said supporting member having an element which is adapted to frictionally hold a portion of said crystal in engagement with said first banking surface.
